CASSETTE DISPLAY RACK

Michael D. Cockcroft, Larchmont, N.Y., assignor to
Mar-Line Displays Inc., Port Chester, N.Y.

Filed Aug. 14, 1974, Ser. No. 497,235

Term of patent 14 years

Int. Cl. D6—04; D20—02

U.S. Cl. D6—157

Fig 1

Fig 2

Fig 3

Fig 4

Fig 5

Fig 6

FIG. 1 is a rear perspective view of a cassette display rack showing my new design;

FIG. 2 is a front elevational view thereof, the cassettes being shown in broken lines for illustrative purposes only.

FIG. 3 is a front elevational view thereof, on a reduced scale;

FIG. 4 is a rear elevational view thereof, on a reduced scale;

FIG. 5 is a sectional view taken along line 5—5 of FIG. 4; and

FIG. 6 is a sectional view taken along line 6—6 of FIG. 3.

I claim:

The ornamental design for a cassette display rack, substantially as shown and described.
